Atty's.

UNITED STATES PATENT OFFICE.

GEORGE L. HARRISON, OF EAST CLEVELAND, OHIO.

DESIGN FOR A SPOUT FOR COOKING UTENSILS.

52,317.

Specification for Design.

Patented Aug. 27, 1918.

Application filed April 28, 1915. Serial No. 24,596. Term of patent 14 years.

To all whom it may concern:

Be it known that I, GEORGE L. HARRISON, a citizen of the United States, residing at East Cleveland, in the county of Cuyahoga and State of Ohio, have invented a new, original, and ornamental Design for a Spout for Cooking Utensils, of which the following is a specification, reference being had to the accompanying drawing, forming part hereof, wherein—

Figure 1 is a front elevation, Fig. 2 a

side elevation, and Fig. 3 a plan of the spout for cooking utensils and the like exhibiting my new design.

I claim:—

The ornamental design for a spout for cooking utensils as shown.

GEORGE L. HARRISON.

Witnesses:

W. E. SHEPPARD,

L. S. CHADWICK.
